UNITED STATES PATENT OFFICE.

WILLIAM H. MINER, OF CHICAGO, ILLINOIS, ASSIGNOR TO W. H. MINER COMPANY, OF CHICAGO, ILLINOIS, A CORPORATION OF ILLINOIS.

DRAFT-RIGGING FOR RAILWAY-CARS.

SPECIFICATION forming part of Letters Patent No. 758,144, dated April 26, 1904.

Application filed May 9, 1903. Serial No. 156,339. (No model.)

To all whom it may concern:

Be it known that I, WILLIAM H. MINER, a citizen of the United States, residing in Chicago, in the county of Cook and State of Illinois, have invented a new and useful Improvement in Draft-Rigging for Railway-Cars, of which the following is a specification.

My invention relates to improvements in draft-rigging for railway-cars, and more particularly to improvements in tandem-spring draft-rigging designed for use upon modern heavy cars and in which the draft-rigging is subjected to very heavy blows or strains. Heretofore in such draft-rigging difficulty has been experienced by reason of the side plates or stop-castings, or the connections thereof with the center sills or draft-timbers, giving way under the extremely heavy blows or strains to which the same are subjected in use upon the large modern cars carrying heavy loads and coupled in long trains.

The object of my invention is to provide a simple, practical, efficient, and economical means for overcoming this difficulty and by which the draft-rigging as a whole and its connection with or anchorage to the center sills or draft-timbers are greatly strengthened, thus adding greatly to the durability and safety of the draft-rigging and of the car.

My invention consists in the means I employ to practically accomplish this important object or result—that is to say, it consists, in connection with the customary draw-bar, tandem springs, followers, and side plates or stop-castings, of extension-anchors or filler-blocks firmly bolted or secured to the center sills or draft-timbers of the car and extending through the body-bolster or transom of the car and having a shouldered connection therewith or abutment thereagainst and connected at their front ends with the rear ends of the side plates or stop-castings of the draft-rigging, so that under buffing blows or strains the side plates or stop-castings will abut directly against these extension-anchors or filler-blocks, and thus be given the additional strength or resistance due thereto and to their connection with the body-bolster or transom, thus not only greatly strengthening the draft-rigging, but mate-

rially relieving the center sills or draft-timbers themselves from excessive strain and distributing the blows or shocks properly to the body of the car itself, and as the side plates or stop-castings at their rear ends are firmly bolted and secured to these extension-anchors or filler-blocks the draft-rigging is similarly strengthened to resist pulling strains.

My invention also consists in the novel construction of parts and devices and in the novel combinations of parts and devices herein shown or described.

In the accompanying drawings, forming a part of this specification, Figure 1 is a side elevation of a railway draft-rigging embodying my invention, showing the body-bolster and transverse beams of the car in cross-section. Fig. 2 is a plan view, partly in horizontal section. Fig. 3 is a cross-section on line 3 3 of Fig. 1, and Fig. 4 is a cross-section on line 4 4 of Fig. 1. Fig. 5 is a side elevation illustrating the application of my invention to a car furnished with draft-timbers. Fig. 6 is a plan view, partly in horizontal section, of the construction shown in Fig. 5. Fig. 7 is a cross-section on line 7 7 of Fig. 5, and Fig. 8 is a cross-section on line 8 8 of Fig. 5.

In the drawings, A A represent the center sills of the car; A', the front sill; A², the buffer-block; A³, the buffer-plate, and A⁴ the carry-iron.

B is the coupler, B' the draw-bar, and B² the draw-bar extension, the same being preferably in the form of a yoke or strap, as illustrated, and secured to the draw-bar by bolts b. The draw-bar and draw-bar extension have shoulders or abutments b' b² b³ to bear against the followers C.

E are the tandem-arranged springs interposed between each pair of followers, the same preferably having smaller springs e e inside the larger springs.

D D are the side plates or stop-castings, the same having shoulders or stops d d' d² for the followers to abut against and upper and lower guides d³ d⁴ for the followers to reciprocate between, the upper guides d³ being preferably cast integral with the side plates

or stop-castings and the lower guides d^4 being made removable or in separate pieces from the stop-castings to enable the draw-bar, springs, and followers to be readily removed and replaced. Each of the side plates or stop-castings D is further provided with an integral web or flange d^5 , which fits under the center sill, and the side plate or stop-casting is firmly secured to the center sill by bolts d^6 , 10 extending horizontally through the center sills, and also by bolts d^7 , extending vertically through the center sills. Each of the side plates or stop-castings D is further provided with a transverse flange or shoulder d^8 , abutting against the front sill A' of the car, and with upright integral flanges d^9 d^{10} , through which bolts d^{10} extend to further secure the stop-casting to the center sill.

F F are the extension-anchors or filler-blocks connected at their front ends by bolts f and interengaging hooks f' f'' with the rear ends of the side plates or stop-castings D and firmly secured to the center sills by bolts f^3 f^4 and extending through the body-bolster or 20 transom G of the car between the upper and lower plates g g' thereof and having a shouldered connection or abutment f^4 with the transom or body-bolster, so that a portion of the strain of the draft-rigging in both pulling 25 and buffing may be transmitted directly to the transom or body-bolster of the car, thus in part relieving the center sills or draft-timbers and the bolts for securing the draft-rigging thereto from strain. The extension-anchors or filler-blocks F fit underneath the center sills and are directly in line with the side plates or stop-castings D or the horizontal web or flange d^5 thereof, as will be readily understood from the drawings.

30 The bolt f , by which the extension-anchors or filler-blocks F are secured to the side plates or stop-castings D, are longitudinal bolts extending in the direction of the parts connected and pass through abutting transverse flanges 35 f^5 and d^{10} on the extension-anchors and side plates, respectively. The connecting-bolts f being longitudinal are thus subjected to no shearing strain or action.

In Figs. 5, 6, 7, and 8 I have illustrated my 40 invention as applied to a car having in addition to the center sills A A the customary draft-timbers A⁵ A⁵, secured beneath the center sills. In this form of my invention the extension-anchors or filler-blocks E F, as in 45 Figs. 1, 2, 3, and 4, are directly behind and in line with the side plates or stop-castings and their front ends connected to the rear ends of said side plates or stop-castings, as before described; but in this modification 50 (illustrated in Figs. 5, 6, 7, and 8) the extension-anchors or filler-blocks F F fit against the inside faces of the draft-timbers instead of against the under side of the center sills, and the same are secured to the center sills 55 through the draft-timbers, which are bolted

or connected to the center sills in the usual manner.

I claim—

1. In a tandem-spring draft-rigging, the combination with a draw-bar, draw-bar extension, springs, followers and side plates or stop-castings, of extension-anchors or filler-blocks secured to and abutting against the side plates or stop-castings and extending through and having a shouldered connection with the body-bolster or transom of the car and secured to the center sills of the car, said side plates or stop-castings and extension-anchors or filler-blocks having at their meeting ends abutting transverse flanges, and connecting-bolts 70 extending through said transverse flanges, substantially as specified.

2. In a tandem-spring draft-rigging, the combination with a draw-bar, draw-bar extension, springs, followers and side plates or stop-castings, of extension-anchors or filler-blocks secured to and abutting against the side plates or stop-castings and extending through and having a shouldered connection with the body-bolster or transom of the car and secured to the center sills of the car, said side plates or stop-castings having webs or flanges fitting under the center sills of the car, said side plates or stop-castings and extension-anchors or filler-blocks having at their meeting ends abutting transverse flanges, and connecting-bolts 80 extending through said transverse flanges, substantially as specified.

3. In a tandem-spring draft-rigging, the combination with a draw-bar, draw-bar extension, tandem springs, followers and side plates or stop-castings, of extension-anchors or filler-blocks connected to and abutting against the side plates or stop-castings, said side plates or stop-castings and extension-anchors or filler-blocks having at their meeting ends abutting transverse flanges, and connecting-bolts 90 extending through said transverse flanges, substantially as specified.

4. In a tandem-spring draft-rigging, the combination with a draw-bar, draw-bar extension, tandem springs, followers and side plates or stop-castings, of extension-anchors or filler-blocks connected to and abutting against the side plates or stop-castings, and having a 100 shouldered connection with the body-bolster or transom of the car, said side plates or stop-castings and extension-anchors or filler-blocks having at their meeting ends abutting transverse flanges, and connecting-bolts 105 extending through said transverse flanges, substantially as specified.

5. In a draft-rigging, the combination with the side plates or stop-castings, of extension-anchors or filler-blocks secured to and abutting against the rear ends thereof, said side plates and stop-castings and extension-anchors or filler-blocks having at their meeting ends interengaging hooks and abutting transverse flanges and connecting-bolts extending 115 120 125 130

through said transverse flanges, substantially as specified.

6. In a draft-rigging, the combination with the side plates or stop-castings, of extension-anchors or filler-blocks secured to and abutting against the rear ends thereof and provided with shoulders engaging the body-bolster or transom under buffing strains on the draft-rigging, said side plates and stop-castings and extension-anchors or filler-blocks having at their meeting ends interengaging hooks and abutting transverse flanges and connecting-bolts extending through said transverse flanges, substantially as specified.

15 7. In a draft-rigging, the combination with

the side plates or stop-castings, of extension-anchors or filler-blocks secured to and abutting against the rear ends thereof, said side plates or stop-castings having integral webs or flanges fitting under the center sills, said side plates and stop-castings and extension-anchors or filler-blocks having at their meeting ends interengaging hooks and abutting transverse flanges and connecting-bolts extending through said transverse flanges, substantially as specified.
